UNITED STATES PATENT OFFICE.

THOMAS R. KENNEDY AND EDWARD J. KING, OF ROCHESTER, NEW YORK, ASSIGNORS TO THE COOPERATIVE FOUNDRY COMPANY, OF SAME PLACE.

DESIGN FOR A FURNACE-FRONT.

SPECIFICATION forming part of Design No. 33,796, dated December 25, 1900.

Application filed November 30, 1900. Serial No. 38,274. Term of patent 7 years.

To all whom it may concern:

Be it known that we, THOMAS R. KENNEDY and EDWARD J. KING, of Rochester, in the county of Monroe and State of New York, have invented and produced a new and original Design for Furnace-Fronts, of which the following is a specification, reference being had to the accompanying drawing, forming a part thereof.

- o The drawing is a front elevation, shown slightly in perspective, of a furnace-front embodying our design.

The leading and characteristic feature of our design is the configuration and surface ornamentation of a furnace-front.

The design consists of a rectangular panel A, having its top and sides bounded by a molding a. The panel is divided into upper and lower sections by a plain molding or band

- o B, and the former is provided with a door C, having the ornamentation c arranged above the damper-openings c', upon either side of which are the ornaments d. Conventional

scroll-and-leaf ornamentation D is provided upon each side of the door C, and beneath the latter are ornaments E of a similar design extending upon opposite sides of the center. The lower section of the panel A is provided with the door F, and above the top of the latter is a scroll-and-leaf design G, and at the sides of the section, near the lower corners of the door, are the ornaments g. The door F is provided at each side with scroll-and-leaf ornaments H, and near its lower edge is located a supplemental door f, having at its center the ornamental figure f', upon either side of which are the ornaments h, and above the said door are aperture-covers I.

We claim—

The design for a furnace-front substantially as shown and described.

THOMAS R. KENNEDY.
EDWARD J. KING.
